VENDING APPARATUS

Harold S. Cohn, Jacksonville, Fla.

Application December 8, 1937, Serial No. 178,797

10 Claims. (Cl. 194—48)

The present invention relates to vending apparatus designed to dispense articles, ordinarily singly, from a stack. While not limited to such use, it is an object of the invention to provide a device which may be of such restricted dimensions and of such external form as to be mountable on the back of a theater seat or the like without objectionably obstructing the usual space in front of a seat therebehind. Other objects are to provide a device of simple and inexpensive construction which will safeguard the articles to be vended, the mechanism of the device itself, and the customer as well.

In order that the principles underlying the invention may be thoroughly understood, I shall describe it with reference to a practical embodiment thereof which I have shown by way of example in the accompanying drawings.

In the drawings:

Figure 1 is a face view of the machine, which is shown as attached to the back of a seat, the latter being shown partially in elevation.

Figure 2 is a section substantially on line 2—2 of Figure 3, a portion of the seat being also shown in section and the view being on a somewhat larger scale than that of Figure 3.

Figure 3 is a section substantially on line 3—3 of Figure 2.

Figure 4 is a section substantially on line 4—4 of Figure 2 and on the same scale as Figure 3.

Figure 5 is a partial view similar to that of Figure 4 but showing in operative position a locking member which serves to lock the apparatus against operation when it is empty.

Figure 6 is a section substantially on line 6—6 of Figure 3, but on the scale of Figure 2.

Figure 7 is a section substantially on the line 7—7 of Figure 4 and on the same scale as Figure 6, and

Figure 8 is an exploded view in perspective of a magazine and counterweight embodied in the apparatus.

Referring to the drawings, the apparatus includes a housing, generally designated at 10, which comprises a base plate 11, here shown as secured to the back of a seat 12, and a cover 13. As shown in Figure 1 the cover, in face view, has a substantially rectangular lower half and a tapered upper half, the base plate having substantially the same configuration. The cover includes the face portion 14, top and bottom walls 15 and 16, and side walls 17 and 18, the said walls forming a continuous flange for the face portion 14 and being of similar depth, except that the top and bottom walls have arcuate edges substan-

tially conforming to the base plate which is transversely curved, as here shown, to conform to the curved back of the seat.

The plate 11 is formed at its upper edge with an outturned lip 19 adapted to be engaged by a downwardly turned lip 20 of the cover wall 15. The cover is thus supported and registered with the base plate, since the sides of lip 20 lie between abutment portions at the ends of lip 19. A latch 21 is fixed to the lower portion of the base plate and projects outwardly of the latter. The latch has a recess 22 engageable by a bolt 23 projectible from a lock 24 mounted on the inside of the lower cover wall 16 and controllable by means of a key which may be introduced through a suitable opening in the wall.

The top wall 15 is provided with a slot 25 which occupies a depressed position by reason of the in-setting of the slot margins. The slot is disposed substantially centrally of the top wall 15 and extends longitudinally of the latter.

The face portion 14 of the cover 13 is provided with an obliquely disposed delivery opening or window 26 whose top and bottom edges may be recessed at 27 and 28 to enable an article behind the opening to be conveniently grasped for removal. The face portion 14 is also provided with an obliquely disposed coin slot 29 which is dimensioned to pass a coin of suitable denomination.

While the device of the present invention is not limited as to articles to be dispensed, the illustrated embodiment is designed to dispense articles in the nature of packages of gum. Consequently, a magazine designed with this end in view is provided and is perhaps most clearly shown in Figure 8. This magazine is of rectangular cross section so as to receive the packages crosswise and to permit them to gravitate freely. The magazine is open at both ends. As shown in Figure 8, the magazine, designated generally as 30, is constituted by a single sheet of metal wrapped to the shape of a parallelepiped, the face portion 31 having an extension or tab 32 lapping in part the side wall 33, its extremity being outwardly bent to provide a rib 34 of uniform depth and spaced inwardly from the adjacent edge of wall 33. The extension 32 and wall 33 may be riveted together and provided with threaded holes 35 for a purpose to be hereinafter described. Wall 31 and the rear wall 36 of the magazine are provided with substantially triangular upward extensions and have registering openings 37 and 38 at their extremities. At its lower portion wall 31 may be provided with lat-

eral extensions or wings 39 and 40. It projects below the remaining walls and may have an arcuate lower edge as shown in Figure 8.

Pivoted on wall 33 at 41 is the extremity of a short arm of an L-shaped latch member 42 whose other arm 43 extends along the rear surface of flange 34 and has an enlarged portion 44 projecting below the latter, the enlargement being on that side of member 43 adjacent the front wall 31 and including a cam surface 45. Due to the manner of mounting the latch, its portion 43 normally hangs toward rib 34 when the magazine is upright. The tendency of the latch to swing in a counter-clockwise direction is enhanced ordinarily by the fact that when mounted, as shown in Figure 2, the magazine is inclined to the vertical.

An elongated counterweight 46 is channeled to provide ribs 47 and 48, the latter having the same depth as the rib 34, and the former being somewhat deeper and being undercut to provide a longitudinally extending recess 49. Rib 48 is interrupted at 50 to provide a recess which defines three sides of a coin slot. The counterweight is assembled with the magazine by passing screws through holes 51 which register with the holes 35. When thus assembled the rib 48 abuts the forward edge of extension 32 and rib 34 abuts the bottom of the counterweight channel. The outer margin of rib 47 overlies the outer margin of wall 36 and recess 49 is in register with latch portion 43 so that the latter may swing freely outwardly a certain distance. The lower portion of the counterweight channel constitutes a downwardly open coin chute in communication with slot 50, the other side of the latter being provided by a portion of the extension 32. The enlarged latch portion 44 constitutes a wall portion of the coin chute.

The relation of parts is such that a coin of 40 suitable denomination, in the present case a five cent piece, passed through slot 50, will drop downwardly in the coin chute and strike cam surface 45 so as to swing latch 42 about pivot 41 in a clockwise direction.

Referring particularly to Figures 2 and 3, a yoke 52 has leg portions secured to the extremities of walls 31 and 36 and provided with openings registering with openings 37 and 38, the axis of these openings being perpendicular to the parallel front and rear magazine walls.

Secured to the top portion of back plate 11 on its vertical axis and perpendicular to the latter, is a stud 53 which passes through the openings 37 and 38 and the yoke openings to pivotally support the magazine which is retained on the stud by means such as a washer 54 and cotter pin 55. Fixed to the cross portion of the yoke is a stud 56 which projects upwardly through the slot 25 and into the pocket thereabove, but not substantially above the cover top wall 15. Stud 56 is of non-round section and is received in a mating opening in an elongated plate 57 slidable thereon and held slidingly against the in-set wall portions around slot 25 by a compression spring 58 which surrounds stud 56. In the operation of the device stud 56 moves from one end to the other of slot 25, but plate 57 is of sufficient length to maintain the slot constantly closed throughout.

With the magazine mounted as described, it normally occupies the position shown in Figure 3 in view of the effect of the counterweight. Movement of the magazine in a counter-clockwise direction beyond the position shown in Figure 3, may be prevented by any suitable means as for

example a stop 59 which is engaged by the lower portion of wall 60 of the magazine.

When the magazine is in the position shown in Figure 3, it is directly above a shelf 61 which is supported, through an apron 62, by a flange 63 riveted to plate 11. The shelf has an end wall 64 of which the stop 59 is a continuation. The shelf is open toward the face 14 of the cover and terminates in adjacency to the latter. To the left the shelf is continued into a second relatively elevated shelf or continuation 65 which is of arcuate form, as shown, substantially on the axis of stud 53, the two shelves being separated by an upward step or wall 66 and the latter and wall 64 being spaced apart a distance a little greater than the length of a package of gum. The shelf 61 is of a width to accommodate such a package and is substantially flush with the lower straight edge of window 26 when the cover is in place.

The left hand end of shelf 65 is continued downwardly as a strip 67 to an upwardly open coin receptacle 68 which has an outer wall 69 and is suitably flanged, as at 70 and 71, for attachment to plate 11, a portion of which constitutes one wall of the receptacle. Flange 71 has an outwardly turned end portion 72 which carries an upwardly extending stud 73. Wall 66 is extended over to plate 11 and provided with a bent extremity 74 riveted to the latter. Wall 66 and its extension are provided with a horizontal slot 75 and adjacent thereto apron 62 has a cut-out 76. The shelves, supporting brackets, coin receptacle, etc., may be bent from a single piece of thin metal.

The inner edge of shelf 65 is spaced from plate 11 a substantial distance and from the back wall 36 of magazine 30 a distance somewhat greater than the maximum thickness of enlargement 44 of the latch member. The rear edge of shelf 65 is rectilinear in plan except for a square notch 77 and a saw tooth notch 78, these being most clearly shown in Figure 7. Notch 77 is slightly wider than the thickness of the enlargement 44 and the latter hangs somewhat below the shelf as shown, for example, in Figure 2.

Pivoted on stud 73, and retained by means such as a cotter pin 79, is a lever, here shown as being made of spring wire with a plurality of turns around the stud to serve as a bearing. One end 80 of the lever projects through slot 75 and behind cut-out 76 in the normal position of the lever and is yieldingly held in this position by a spring 81. The other end of the lever is provided with a substantially hairpin bend at 82 and its extremity 83 is bent down into contact with the plate 11 and acts, in conjunction with spring 81, to hold the lever portion 80 in the normal position above described. That portion of the lever lying between the extremity 83 and the bend 82 occupies a normal position most clearly shown in Figure 6 wherein it is engageable by the magazine 30 as the latter is swung in a clockwise direction about stud 53, the swing in this direction being limited, by any suitable means, to the angular relation shown in Figure 4. In striking the described portion of the lever the same is cammed toward plate 11 thereby swinging lever portion 80 outwardly along slot 75, through cut-out 76, and horizontally over the left hand end of shelf 61 to engage the adjacent portion of an article on the shelf whereby the latter is given an ejecting movement.

With the magazine loaded and in the right hand limit position, as shown in Figure 3, its down-

wardly open lower end overlies shelf 61 and the lowermost article of the stack rests on the shelf and supports the remaining articles in the magazine. Enlargement 44 of latch 42 is engaged in notch 77 so that the magazine is locked in the angular position of Figure 3. Coin slot 29 of the cover is in exact register with the coin slot on the magazine and the lower portion of magazine wall 31 constitutes a shield which completely closes the window 26 of the cover.

A coin inserted through the registering slots drops down the coin chute, strikes cam surface 45 of latch 42, thereby moving the enlargement 44 out of notch 77, and then comes to rest on the right hand portion of shelf 65, still holding the latch disengaged. If stud 56 is now grasped and moved to the right, the magazine may be swung to the left hand position shown in Figure 4. The lowermost package is held by abutment wall or step 66 on shelf 61, whereas the remaining packages are retained in the magazine by shelf 65. The coin slides over shelf 65, holding the latch from engagement with notch 78, and eventually falls off the left hand edge of shelf 65 into the coin receptacle 68. In the meantime, lever arm 80 has been urged toward ejecting position, as above described, bearing the article on shelf 61, against the lower margin of magazine wall 31, and when the latter clears the window 26 the arm 80 acts to push the package to the partially ejected position indicated in Figure 7 wherein it may be conveniently grasped through the recesses 27 and 28. It will be evident that since the left hand end of the package lies in front of the right hand lower edge of the extension 40 of magazine wall 31, the magazine cannot swing to the right until the package has been removed. Upon removal of the package the magazine returns to its right hand limit position under the influence of the counterweight and the lowermost package in the magazine is deposited on shelf 61 in readiness for the next vending operation.

Resting on the top of the stack in the magazine is a stack follower 84 formed of a strip of metal freely slideable in the magazine and supported on the stack by terminal off-set portions 85 and 86 which are extended into parallel upright portions 87 and 88. When the magazine is swung to the left from the last remaining package the follower 84 will slide over shelf 65 until the off-set 85 drops over the left hand edge of the shelf so that extension 87 serves to block the return of the magazine. When the magazine is to be charged the cover is removed and off-set 85 pushed upwardly so that the magazine in its return will carry the follower onto shelf 61. Latch 42 is then released and the magazine swung to the left so that the follower can be taken from shelf 61 and again placed in the reloaded magazine.

Since the follower 84 serves to hold the empty magazine against return, it is evident that the coin slot of the magazine is held out of register with the coin slot 29 of the cover so that no coin can be inserted.

Rib 34 serves to prevent tampering with the latch 42 through the coin slots when the latter are in register, but even if it is succeeded, by means of a thin instrument, in moving the latch out of notch 77, the instrument must then be removed and the latch will engage in slot 78 to prevent further movement of the magazine to the left.

The coin chute is so proportioned that a smaller coin, such as a one cent piece, will not suffice to

move the latch from notch 77. Of course, usual provisions for preventing operation by iron slugs or the like may be incorporated.

It will be seen that the described machine is of very simple construction and involves a minimum of moving parts. Springs, in the preferred embodiment of the invention, are for the most part displaced by gravity action. The device is very effective in operation, fully safe-guarding the articles to be vended as well as its own operating parts, preventing fraudulent operation by a coin or slug smaller than that intended, and preventing the insertion of a coin when the articles have all been sold.

The thickness of the housing need be but little greater than that of the magazine and when kept at a minimum the apparatus is particularly adapted for disposition in a restricted space. The absence of projecting parts is another advantageous feature.

Obviously, many changes in the form and manner of association of the parts are possible without departure from the invention and consequently I do not limit myself to these matters except as in the following claims.

I claim:

1. Vending apparatus comprising a housing, a magazine pivoted in the housing on a horizontal axis and having a downwardly directed opening, said magazine being swingable between limit positions, a fixed shelf beneath said opening when said magazine is in one of said positions and adapted to support a stack of articles of which all except the lowermost are in the magazine, an abutment at one end of said shelf restraining said lowermost article against movement with said magazine when the latter is swung to its other limit position, and a second fixed shelf supporting the remainder of the articles in the magazine when the latter is swung to said other limit position, return of said magazine subsequent to the removal of said lowermost article from the first shelf depositing the succeeding article on the latter.

2. Vending apparatus comprising a housing, a magazine pivoted in the housing on a horizontal axis and having a downwardly directed opening, said magazine being swingable between limit positions, a fixed shelf beneath said opening when said magazine is in one of said positions and adapted to support a stack of articles of which all except the lowermost are in the magazine, an abutment at one end of said shelf restraining said lowermost article against movement with said magazine when the latter is swung to its other limit position, a second fixed shelf supporting the remainder of the articles in the magazine when the latter is swung to said other limit position, return of said magazine subsequent to the removal of said lowermost article from the first shelf depositing the succeeding article on the latter, a downwardly open coin chute carried by the magazine and blocked by said second shelf to prevent escape of a coin therefrom when the magazine is being moved from said first limit position toward said other limit position but unblocked when the last-named position is reached so as to release the coin, a magazine latch held released by the coin while the coin is retained in said chute, and a receiver arranged to receive the released coin.

3. Apparatus according to claim 1 wherein a stack following member is provided which is adapted to engage an end of said second shelf when the stack is exhausted to prevent return of said magazine.

4. Vending apparatus comprising a housing, a magazine in said housing movable in a dispensing operation between limit positions said housing and magazine having substantially parallel wall portions provided with coin slots which register only when the magazine is in one of its limit positions, the housing wall portion covering the magazine slot when the magazine is in other than said one of its limit positions.

5. Vending apparatus comprising a housing, an open-ended magazine in said housing movable laterally between limit positions, a fixed abutment in the housing extending lengthwise of and adjacent to the open end of said magazine when the latter is in one of said positions and adapted to support against outward movement relative to the magazine a group of articles of which all but the outermost are in the magazine, and means for retaining said outermost article against said abutment as the magazine and therewith the remainder of said articles are moved to the other limit position of the magazine, said housing having a dispensing opening through which said outermost article is directly accessible for removal when said magazine is swung to said other limit position, return of said magazine subsequent to the removal of said outermost article from said abutment bringing the succeeding article into position to be received against said abutment, said magazine including a portion covering said dispensing opening when the magazine is in said one of said positions and uncovering said opening when the magazine is moved to said other limit position.

6. Vending apparatus comprising a housing, an open-ended magazine in said housing movable laterally between limit positions, a fixed abutment in the housing extending lengthwise of and adjacent to the open end of said magazine when the latter is in one of said positions and adapted to support against outward movement relative to the magazine a group of articles of which all but the outermost are in the magazine, an angular abutment at one end of the first abutment restraining said outermost article against movement with said magazine when the latter is swung to its other limit position, and a further abutment supporting the remainder of the articles in the magazine as the latter is swung to said other limit position, return of said magazine subsequent to the removal of said outermost article from the first abutment bringing the succeeding articles into position to be received against said first abutment.

7. Vending apparatus comprising a housing, a magazine in said housing movable in a dispensing operation from a normal position at one side of the housing toward the opposite side of the housing, a coin chute carried by said housing through which a coin may gravitate, a movable latch defining a side portion of said chute, a fixed stop portion normally engaged by said latch, said latch having a cam portion engageable by a coin of proper size in the chute to move the latch from normal magazine-locking position whereby to render the latch inoperative, a slot in said housing through which a coin may be introduced to the chute when the magazine is in normal position, and means for maintaining the

coin in engagement with said cam portion while the magazine is moved toward said opposite side of the housing and then releasing the coin as the limit of such movement of the magazine is reached.

8. Vending apparatus comprising a housing and dispensing means in said housing, said dispensing means including a stack-receiving magazine in said housing movable between limit positions, said housing being provided with a coin slot, a coin chute carried by the magazine for the reception of a coin inserted through said slot, a coin controlled latch member carried by said magazine and constituting a wall portion of said chute, and a fixed stop portion normally engaged by said latch member, said latch member being engageable by a coin of proper size introduced into the chute to be moved by the coin to unlatching position to permit dispensing movement of said magazine.

9. Vending apparatus comprising a housing, an open-ended magazine in said housing movable laterally between limit positions, a fixed abutment in the housing extending lengthwise of and adjacent to the open end of said magazine when the latter is in one of said positions and adapted to support against outward movement relative to the magazine a group of articles of which all but the outermost are in the magazine, means for retaining said outermost article against said abutment as the magazine and therewith the remainder of said articles are moved to the other limit position of the magazine, said housing having a dispensing opening through which said outermost article is directly accessible for removal when said magazine is swung to said other limit position, return of said magazine subsequent to the removal of said outermost article from said abutment bringing the succeeding article into position to be received against said abutment, and means actuated as a result of movement of said magazine toward said other limit position to impart ejecting movement to said outermost article.

10. Vending apparatus comprising a housing, an open-ended magazine in said housing movable laterally between limit positions, a fixed abutment in the housing extending lengthwise of and adjacent to the open end of said magazine when the latter is in one of said positions and adapted to support against outward movement relative to the magazine a group of articles of which all but the outermost are in the magazine, means for retaining said outermost article against said abutment as the magazine and therewith the remainder of said articles are moved to the other limit position of the magazine, said housing having a dispensing opening through which said outermost article is directly accessible for removal when said magazine is swung to said other limit position, return of said magazine subsequent to the removal of said outermost article from said abutment bringing the succeeding article into position to be received against said abutment, said magazine having a portion engageable with a partially ejected article to prevent return of the magazine until such article has been removed from the abutment.

HAROLD S. COHN.
